United States Patent Office

Des. 212,074
Patented Aug. 27, 1968

212,074

CARRYING CASE FOR BOTTLES OR THE LIKE

William W. Woodruff, Signal Mountain, and Vance E. Rhinehart, Apison, Tenn., assignors to Cumberland Corporation, Chattanooga, Tenn., a corporation of Tennessee

Filed Aug. 17, 1967, Ser. No. 8,302

Term of patent 14 years

(Cl. D9—177)

Fig. 1.

Fig. 2.

Fig. 3.

Fig. 4.

FIG. 1 is a perspective view of a carrying case for bottles or the like showing our new design;

FIG. 2 is a side elevation thereof;

FIG. 3 is a top plan view thereof; and

FIG. 4 is a bottom plan view thereof on an enlarged scale.

We claim:

The ornamental design for a carrying case for bottles or the like, substantially as shown.
